DISPENSER TOP FOR A PRESSURE CONTAINER

William C. Harris, Racine, Wis., assignor to S. C.
Johnson & Son, Inc., Racine, Wis.

Filed Feb. 18, 1963, Ser. No. 73,594

Term of patent 14 years

(Cl. D58—26)

Fig. 1.

Fig. 2.

Fig. 3.

Fig. 4.

Fig. 5.

FIG. 1 is a side elevational view of a dispenser top for a pressure container, embodying my new design;
FIG. 2 is a front elevational view;
FIG. 3 is a rear elevational view;
FIG. 4 is a top plan view; and
FIG. 5 is a perspective view thereof.

I claim:

The ornamental design for a dispenser top for a pressure container, substantially as shown.
